[57] **CLAIM**

The ornamental design for a frame for barbell or the like, as shown and described.

DESCRIPTION

FIG. 1 is a perspective view from above of a frame for barbell or the like showing my new design;

FIG. 2 is a bottom perspective view thereof;

FIG. 3 is an end elevational view thereof, the end opposite being substantially a mirror image; and,

FIG. 4 is a side perspective view thereof, the side opposite being substantially a mirror image.

Fig.1

Fig.4
